United States Patent Office.

ALLAN NEILSON, OF ALLEGHENY CITY, PENNSYLVANIA.

Letters Patent No. 70,882, dated November 12, 1867.

IMPROVED WASHING MACHINE.

The Schedule referred to in these Letters Patent and making part of the same.

TO ALL WHOM IT MAY CONCERN:

Be it known that I, ALLAN NEILSON, of Allegheny City, in the county of Allegheny, and State of Pennsylvania, have invented a new and improved Washing Machine; and I do hereby declare that the following is a full, clear, and exact description thereof, which will enable others skilled in the art to make and use the same, reference being had to the accompanying drawings, forming part of this specification, in which—

Figure 1 represents a vertical sectional view of my improved washing machine.

Figure 2 is a plan or top view of the same, partly in section.

Similar letters of reference indicate like parts.

This invention relates to a washing machine in which two or more corrugated conical rollers are secured in such a manner in a swinging frame above a flexible wash-board, that their axes cross each other, while their under surfaces are with their whole length on the said board, so that by oscillating the said frame the rollers will rotate on their larger diameters, and slip on their smaller end, and will thus at once beat and rub the clothes to be washed.

A represents a suds-box of usual construction, supported upon legs B B. Two upright posts, b, are arranged at its sides, and between them is pivoted a frame, C, that is provided with a handle, D, and can thereby receive an oscillating motion. To the lower end of the frame C are secured suitable bearings for two or more corrugated conical rollers E E, which are arranged so that the larger end of one is at the same side of the box A with the smaller end of the next, and *vice versa*. The under surface of each of these rollers is perfectly level, and they are arranged in respect to each other in such a manner that their undersurfaces conform to the shape of the wash-board G below. The latter is made of laths, rounded or V-shaped at their upper edge, all the laths being connected by means of strings or wires a a, as shown. The lower inner end of the board, or the last lath inside of the suds-box, is firmly secured to the bottom or sides of the box A, or to springs which are fastened to the box. The ends of the strings or wires connecting the different laths are there secured, or are there connected with each other, and the cords or wires then passed through all the laths over or around the edge of the box A to a treadle, F, whereby the board G can be more or less straightened, so as to increase the pressure upon the rollers E, more or less, as is indicated by red and black lines in fig. 1. A soap-box, H, may be connected on the outside of the strings or wires, or independent thereof, as may be desired.

It will be seen that this machine is of very simple construction and easily operated, and can be made almost wholly without metal, and altogether without springs or other weak devices. By means of the treadle it can be operated so as to be adapted for washing different kinds of garments.

What I claim as new, and desire to secure by Letters Patent, is—

1. The corrugated conical rollers E, when arranged with level lower surfaces, and when secured to a swinging frame, C, the axes of which rollers cross each other, substantially as and for the purpose herein shown and described.
2. The flexible wash-board G, consisting of laths, that are secured together by strings or wires a a, and operated by a treadle, F, substantially as set forth.
3. The combination of the treadle F, cords a, box H, and flexible board G with each other and with the rollers E, all made and operating substantially as herein shown and described.

ALLAN NEILSON.
